UNITED STATES PATENT OFFICE.

OLIVER W. RANDOLPH, OF MCCLURE, OHIO.

BROODER.

SPECIFICATION forming part of Letters Patent No. 669,856, dated March 12, 1901.

Application filed April 9, 1900. Serial No. 12,226. (No model.)

To all whom it may concern:

Be it known that I, OLIVER W. RANDOLPH, a citizen of the United States, residing at McClure, in the county of Henry and State of Ohio, have invented a new and useful Improvement in Brooders, of which the following is a specification.

My invention relates to improvements in brooders, and has for its objects to provide an efficient artificial substitute for the mother hen for the brooding of young chicks, in which a uniform heat centrally applied is radiated downward upon the chicks, keeping their bodies warmer than their feet and legs; furthermore, that is provided with a brooding-chamber that is free from corners wherein the chicks may be injured from crowding, readily accessible for cleansing, efficiently lighted, evenly heated and ventilated, and provided with a convenient adjustable runway adapted to admit access to the open air either on or off the ground, and finally to provide a brooder in which either air or water may be used as a medium of heat distribution. I accomplish these objects as illustrated in the drawings and hereinafter described.

In the drawings, Figure 1 is a transverse section in perspective of my invention with an air-heater applied and showing a runway inclined to the ground. Fig. 2 is an interior plan view of my invention. Fig. 3 is an enlarged transverse section of a ventilator-slide. Fig. 4 is transverse section with a water-heater applied and with a runway raised and closed.

Referring to the drawings, A is the casing of the brooder, comprising a cylindrical wall 1, having a vestibule 2, runway doors or openings 3, windows 4, ventilator-openings 5, a bottom 6, having a central orifice 7, legs 8 for supporting the casing, a top 9, having a central orifice 10, a detachable hood 11, forming a roof for the brooder, having a central ventilator 12 at its apex, and handles 13.

The bottom 6 is provided with a metallic lining-tube 14 for orifice 7, projecting within and without the casing, having a supporting-ledge 15, provided with a vertical flange 16, concentric with the tube and supporting a concentric screen 17, and having asbestos or other suitable fireproof lining interposed between the ledge 15 and the bottom 6.

Secured to the bottom 6, at one side of orifice 7 and depending therefrom, is a lamp-bracket 18, having a shelf 19, hinged at one end to the lower end of bracket 18 and provided at the other with a staple or eye 20, adapted to engage a hook 21, pivotally dependent from the bottom 6, and support the shelf 60 in a horizontal position beneath orifice 7.

Suspended from top 9 through orifice 10 by cleats 22, secured to a top closure-disk 23, adapted to fit easily into orifice 10 and provided with a concentric overlapping rim 24, adapted to complete the closure of the orifice, is an adjustable heater B, comprising an inverted hollow metallic cone having a base 25 of equal diameter with disk 23, to which it is adjustably secured by thumb-nut 70 bolts 26, with an asbestos lining 27 interposed, and having its apex cut away and provided with a flue 28, conical at its upper end, cylindrical and open at its lower end, and extending through the lining-tube 14 of orifice 7 in bottom 6. Secured concentrically to the flue 28 and diverging downward therefrom is a conical hood 29, adapted to enter the tube 14 and close the annular opening around the flue 28.

Through the base 25 and disk 23 draft-tubes 30 are provided of sufficient length to allow the heater B to be lowered by bolts 26 and adjusted in the position desired.

Supported on shelf 19 is a lamp 31, having an inverted conical metallic chimney 32, provided with mica windows 33, by which the condition of the flame may be observed, and adapted at its upper end to enter the cylindrical portion of the base of the flue 28 of the heater B and close its lower end, thereby completing the closure of both orifices 7 and 10.

By this construction it is apparent that when the lamp 31 is lighted it will heat the air in heater B and that the air in the circular hover-chamber formed by the wall 1 and the screen 17 will be heated mainly from the top downward. The ventilator-openings 5 are preferably placed less than the height of a chick above the bottom 6 in the wall 1, whereby as the body of air above becomes heated the expansion of the air will force a portion of the colder air below out of the ventilator-openings until the entire body of air down to the level of the ventilator-openings becomes

heated, when warm air will escape, leaving a zone of cooler air at the bottom about the feet and legs of the chicks, which will be maintained by fresh air through the runway-5 openings located at the bottom, drawn in to supply the warm air escaping through the ventilators, and thus producing a condition similar to natural brooding and essential to the strength and health of the chicks.

10 The heater may be lowered in the hover-chamber by bolts 26 when desirable to have the heat radiation move directly upon the brood. The screen 17, which is preferably made of open-meshed wire and designed to 15 keep the chicks from direct contact with the heater without obstructing the heat radiation, is limited in height to allow the heater to be lowered.

An adjustable water-heater C, as shown in 20 Fig. 4, is also provided, in general form and construction similar to air-heater B and having similar means of adjustment, which, as desired, may be substituted therefor, but having the central body portion enlarged and 25 provided with a central funnel-shaped flue 34, having a cylindrical top portion 35, extending through a central orifice 36 in a top closure-disk 23, and with a filling-tube 37, also extended through disk 23. The lower end of 30 flue 34 is also provided with a cylindrical base extension 38, extending through lining-tube 14 of orifice 7, and is provided with a hood 29, adapted to close the annular opening around the flue, which is also adapted to 35 receive the lamp-chimney 31. The heater C being filled with water, the water is heated by flue 34, and the heat is uniformly radiated downward therefrom into all parts of the hover-chamber, as from heater B.

40 By the circular form of the hover-chamber the crowding of chicks into corners, often resulting in the crushing or smothering of the weaker ones, is wholly avoided. By removing the roof-hood 11 the heater B or C (which ever may be in use) and the lining-tube 14, together with the screen 17, may be lifted out, and every part of the hover-chamber is thereby made easily accessible through orifice 10 for cleansing, the old litter and dirt therein 50 being readily swept out through orifice 7 and fresh litter for the floor substituted.

To place the lamp in position for heating the brooder, shelf 19 is dropped to a vertical position, the top of the lamp-chimney is inserted within the lower end of the flue of the heater, and the shelf 19 is then raised and secured in a horizontal position by hook 21, whereby the lamp is supported by the shelf, with the top of the chimney within and contacting with the inner surface of the heater-flue. To insure the lamp from being blown out by the wind, a hood 39, provided with an opening 40 for the chimney and with air-inlets 41, is provided.

65 Hinged to the bottom of vestibule 2 of the casing A is a runway 42, having sides 43, a bottom 44, and an end door 45, hinged to the

bottom 44, adapted to close the outer end of the runway. Door 45 opens outwardly and is provided with legs 46, which when the door 70 is closed, as shown in Fig. 4, are in position to support the runway in a horizontal position above the ground on a level with the bottom of the brooder-casing A. By opening the door 45 the legs 46 are folded underneath 75 the bottom 44, in which position the outer end of the runway may be lowered to the ground, as shown in Fig. 1, to form an incline by which the chicks may pass from the brooder to the ground and return. The sides 80 43 of the runway are connected to the sides of the vestibule 2 by any suitable connection 47, of flexible fabric, adapted to fold together when the runway is raised to a horizontal position and to unfold to close the triangular 85 gaps between the sides of the runway and the sides of the vestibule when the runway is lowered to form an incline.

Ventilator-openings 5 are provided with a sliding shutter 48, adapted to slide in ways 90 49, by which any number or all of the ventilator-openings may be closed.

Windows 4 are formed by fitting panes of glass into suitable frames hinged to the wall 1 of casing A, provided with suitable openings therefor.

Hood 11 is made large enough at the base to receive the top of casing A within it and rest upon it. In this position it forms a roof for the brooder and provides an upper chamber adapted to be heated by the heat escaping through the flue of the heater, thereby further utilizing the heat generated to keep the entire top of the casing warm and in retaining the heat within the brooding-chamber. 105

Having thus fully described my invention, what I claim to be new, and desire to secure by Letters Patent, is—

1. In a brooder, the combination with a cylindrical housing mounted on supports and having orifices, one central through the top, and another central through the bottom of the housing, both concentric with the housing-wall, of a removable closure for the orifice in the top, seated therein, a heater secured to 110 and suspended from the top closure, within and centrally through the chamber of the housing, and removable therefrom by removing the closure, said heater being conically enlarged toward its top, and adapted at its 115 bottom end, when so suspended, to close the orifice in the bottom or floor of the housing, and provided with a hot-air-inlet flue through its bottom, and with one or more outlet-flues extended through the top closure, and a 120 meshed screen within the housing-chamber around the heater, concentric with the wall of the housing, substantially as shown and described and for the purpose set forth.

2. In combination in a brooder, a cylindrical casing, mounted on supports and provided with runway and ventilator openings, a top and a bottom for the casing, each provided with a central orifice concentric with the cas-

ing-wall, a removable closure for the orifice in the top, seated therein; a heater adjustably secured to and suspended from the top closure, within and centrally through the 5 chamber of the casing, and removable therefrom by removing the closure, said heater being adapted, at the bottom, to close the orifice in the bottom of the casing, and having an air-inlet flue at the bottom and an outlet- 10 flue through the top closure, a lamp suspended centrally beneath the casing, a chimney for the lamp connected with the inlet-flue of the heater, a screen within the casing around the heater, and a conical hood open at the 15 base and the apex, adapted to rest over and upon the casing and form a detachable roof and an upper chamber therefor, substantially as shown and described, and for the purpose specified.

20 3. In a brooder, the combination with a housing mounted on standards and having

runway-openings, of a vestibule for the runway-openings secured to the housing, and provided with sides, a runway hinged at one end to the floor of the vestibule and having 25 sides connected with the sides of the vestibule by folding fabric connections, a door adapted to close the opening between the sides at the outer end of the runway, hinged to the floor of the runway and adapted to 30 open outwardly, legs secured to the door, adapted to support the runway in a horizontal position when the door is closed, and to fold beneath the runway when the door is opened and the runway is inclined to the ground, 35 substantially as shown and described.

In witness whereof I have hereunto set my hand this 24th day of March, A. D. 1900.

OLIVER W. RANDOLPH.
